UNITED STATES PATENT OFFICE

2,466,901

CLAMP OR ANCHORAGE

Fred G. Krueger, Norwood, Ohio

Application May 12, 1947, Serial No. 747,527

5 Claims. (Cl. 173—269)

1

This invention relates to a clamp or anchorage, which may be found effective for use wherever a wire, cable, or rod is to have an end securely anchored to a foundation or support. It is especially adapted for use as a clamp for twisted or other multiple-strand electric conductors, as where an end of such conductor is to be attached to a terminal lug, bus connector, or the like.

An object of the invention is to provide a clamp or anchorage device of the character stated, which has great gripping and holding power.

Another object is to provide such a clamp or anchorage, which is capable of effecting a highly effective electric current conducting connection, without damaging or weakening the conductor or its individual strands.

A further object of the invention is to provide a clamp or anchorage device of the character stated, which is simple and inexpensive to manufacture, easy to apply, and durable and lasting in service.

The foregoing and other objects are attained by the means described herein, and illustrated upon the accompanying drawing, in which:

Fig. 1 is a side elevational view of the clamp or anchorage device, holding a multiple-strand electric transmission cable.

Fig. 2 is a cross-sectional view taken on line 2—2 of Fig. 1.

Fig. 3 is an elevational view of the set screw and pressure screw assembly forming part of the device.

Fig. 4 is a view similar to Fig. 1, showing the invention applied to a bus bar clamp.

Fig. 5 is a detail view showing in elevation a slug of deformable material used in conjunction with the device, this slug differing from a corresponding slug incorporated in Figs. 2 and 3.

Fig. 6 is a cross-sectional view taken on line 6—6 of Fig. 4.

Although the improved clamp or anchorage device is herein disclosed as a terminal connection means for multiple-strand electricity conducting wire or cable, it must be understood to have various other uses, such as an anchorage for guy wires, tow lines, suspension cables, and the like. Apart from its superior gripping power, however, the device of the invention possesses an unusual ability to produce an electric conductive connection in which a minimum of resistance to current flow is offered. In this respect, the new clamp or anchorage is greatly superior to others which tend to squash and reduce the cross-sectional area of the conductor strands, with the results of weakening the conductor at the anchorage, and set-

2

ting up a localized resistance to passage of electric current. Unlike many of the older type terminal clamps, the present clamp shows no tendency to eventually relax its hold on the conductor and allow it to wobble or shift and become loose at the connection.

As illustrated upon the drawing, the new clamp or anchorage device makes use of a ductile or deformable metal, such as lead or any soft alloy, having the ability to permeate and fill the spaces or voids between the strands of the conductor when placed under high pressure. This is accomplished by means of a powerful dispersing action inherent in the clamp structure, and without the use of heat to melt or fuse the ductile metal or filler substance, which preferably is itself a conductor of electricity. The aforesaid dispersal of the filler substance amongst the conductor strands, substantially within the limits of the clamp body, increases the volume or density of the conductor at the connection, and thereby forms the desired tight connection of low resistance conductivity.

Referring now more particularly to the examples illustrated upon the drawing, 7 indicates a rigid body of bronze, copper, or other suitable electric conductive metal, having a transverse bore 8 in which is slidably inserted the bared end 9 of a conductor or cable. The conductor may be of the multiple strand type as shown, and will usually but not necessarily always carry an insulating jacket or sheath 10. The body may be provided with a tongue 12 or other form of means to anchor or connect the body electrically as well as mechanically, to a support of any kind, such as a bus bar, terminal panel, or the like. Tongue 12 may be integral with the cylindrically bored body 7.

As is readily understood in this art, the connection between the conductor end and the wall of bore 8 must be tight and also electrically complete to avoid the occurrence of resistance to flow of electric current through the connection. It is of importance in tightening such a connection, to avoid mutilating and weakening the individual strands of the conductor, as any such injury obviously impairs the effectiveness of the connection, shortens its useful life, and may also create an undesirable electrical resistance. These have been common faults in prior connectors, and their elimination constitutes an objective of the present invention.

As illustrated by Figs. 1, 2 and 3, the body 7 is bored as at 13, substantially at right angles to bore 8, and these bores intersect. Bore 13 is

internally threaded to receive the corresponding threads 14 of a hollow or axially bored set screw 15, one end of which has a head 16 to receive a rotating tool or wrench for forcefully advancing the inner end 17 of the set screw into the bore 13. The axial bore 18 of the hollow set screw is internally threaded at 19 to engage the threads 20 of a pressure screw 21. The head of this pressure screw is adapted to receive a wrench or rotating tool, whereby the screw may be driven through the set screw bore and toward the conductor end 9. The lower end of the pressure screw is indicated at 22.

The pressure screw 21 is adapted to drive very forcibly against and between the conductor strands, a mass of deformable material such as lead or any soft or ductile metal having the property of electric conductivity, and the ability to fill the voids or spaces between the conductor strands, thereby to increase the density of the conductor within the confines of the body bore 8. The mass of deformable material initially may be in the form of a slug 23 having a head 24 and a shank 25, or alternatively, it may consist of simply a cylindrical short bar or rod as indicated by the character 23A of Fig. 5. In either case, the slug will extend at least partially within the axial bore 19 of the set screw, so that the advancing force of the pressure screw may be applied to the slug for driving it forcefully against the conductor and dispersing the material thereof throughout the voids and spaces between the conductor strands. Because of the reduced diameter of the pressure screw and the limited area of its advancing end 22, a very powerful force is available for deforming the slug and causing it to "flow" through the interstices of the conductor. This action of the slug material literally expands the conductor within the body bore 8, increases its density to a maximum degree, and thereby enhances the current conductivity property of the connection without mashing, mutilating, and weakening the conductor strands. A connection so made will obviously be mechanically strong and very tight, and will remain so, resulting in great dependability of the connection indefinitely. The possibility of destructive arcing and heating of the connection is thereby completely overcome, this being a consideration of primary importance to the invention.

While in the foregoing explanation it has been made to appear that the advancing end of the pressure screw may bear directly upon the deformable slug 23 or 23A, some advantage may be realized by interposing between these elements a sealer disc 27 of hard non-deformable material, the function of which is to minimize any tendency for the slug material to creep or extrude upwardly along the threads of the pressure screw during the clamping operation. The sealer disc may be of metal, or any hard material which will not fracture or disintegrate under the force of advancement of the pressure screw. The disc should preferably fit rather snugly within the set screw bore 19, as will be appreciated. The disc, of course, is slidable within said bore and advances with the pressure screw.

In Fig. 4, the invention above described is shown applied to a bus bar clamp consisting of the clamp plates 28 and 29 movable toward one another by tightening the nuts 30 upon the screws 31. The body of this clamp is indicated at 32 and carries a plurality of perforated ears or lugs 33 bored and internally threaded to receive the screws 34 which clamp a cover 35 onto the body.

The screws 34 pass through perforated ears or lugs 36 of the cover. When the cover is applied to the body and tightened down by means of the screws 34, the concave elongated pad 38 initially 5 clamps the bared end of a conductor 37. Cover 35 is supplied with a set screw and pressure screw arrangement 16A-21A like that of Fig. 2, which performs as an auxiliary compressor and lock to effect the tight current conductive connection as 10 previously described herein.

The purpose of the Fig. 4 disclosure is to indicate that the means of the invention may be applied to various forms of terminal devices which require secure connections of the character herein disclosed. Accordingly, it is to be understood that various modifications and changes in the structural details of the device may be made, within the scope of the appended claims, without departing from the spirit of the invention.

What is claimed is:

1. In a device of the class described, the combination of a rigid metallic body having a passageway to accommodate a portion of a member to be anchored, said body being bored transversely of the passageway intermediate the ends of the latter, a screw thread formed internally of the bore, a set screw having external threads engaging the threads of the bore, said set screw having an axial internally threaded bore, and a head 20 exposed exteriorly of the body to receive a wrench, a pressure screw having external threads to engage the internal threads of the set screw, a head on the pressure screw extending beyond the head of the set screw for reception of a wrench, and a slug of deformable material in the set screw bore 25 to be advanced against the member to be anchored by rotation of the pressure screw.
2. In a device of the class described, the combination of a rigid metallic body having a passageway to accommodate a portion of a member to be anchored, said body being bored transversely of the passageway intermediate the ends of the latter, a screw thread formed internally of the bore, a set screw having external threads 40 engaging the threads of the bore, said set screw having an axial internally threaded bore, and a head exposed exteriorly of the body to receive a wrench, a pressure screw having external threads to engage the internal threads of the set screw, 45 and a head on the pressure screw extending beyond the head of the set screw for reception of a wrench, a slug of deformable material in the set screw bore 50 to be advanced against the member to be anchored by rotation of the pressure screw, and means interposed between the slug and the advancing end of the pressure screw, to block dispersal of the slug material along the pressure screw threads in the direction of the screw heads.
3. In a device of the class described, the combination of a rigid metallic body having a passageway to accommodate a portion of a multiple-strand cable to be anchored, said body being bored transversely of the passageway intermediate the ends thereof, a screw thread formed internally of the bore, a set screw having external threads 60 engaging the threads of the bore, said set screw having an axial internally threaded bore, and a head exposed exteriorly of the body to receive a wrench, a pressure screw having external threads to engage the internal threads of the set screw, 65 and a head on the pressure screw extending beyond the head of the set screw for reception of a rotary tool, and a slug of deformable electric current conducting metal in the set screw bore 70 to be advanced by rotation of the set screw.
- 75

and dispersed thereby throughout the spaces between the cable strands, for increasing the effective density of that portion of the cable which is within the passageway, thereby to effect a tight and solid anchorage and a low resistance electrical connection between the metallic body, the cable strands, and the interspersed deformable metal.

4. In a device of the class described, the combination of a rigid metallic body having a passageway to accommodate a portion of a multiple-strand cable to be anchored, said body being bored transversely of the passageway intermediate the ends thereof, a screw thread formed internally of the bore, a set screw having external threads engaging the threads of the bore, said set screw having an axial internally threaded bore, and a head exposed exteriorly of the body to receive a wrench, a pressure screw having external threads to engage the internal threads of the set screw, and a head on the pressure screw extending beyond the head of the set screw for reception of a rotary tool, and a slug of deformable electric current conducting metal in the set screw bore, to be advanced by rotation of the set screw and dispersed thereby throughout the spaces between the cable strands, for increasing the effective density of that portion of the cable which is within the passageway thereby to effect a tight and solid anchorage and a low resistance electrical connection between the metallic body, the cable strands, and the interspersed deformable metal.

ble metal, and a hard non-deformable sealer disc in the set screw bore interposed between the slug and the advancing end of the pressure screw.

5. In a device of the class described, the combination of a rigid metallic body having a passageway to accommodate a portion of a member to be anchored, said body being bored transversely of the passageway intermediate the ends of the latter, a screw thread formed internally of the bore, a set screw having exterior threads engaging the threads of the bore, said set screw having an axial internally threaded bore and a head exposed externally of the body to receive a wrench, a pressure screw having exterior threads to engage the internal threads of the set screw, a head on the pressure screw accessible exteriorly of the set screw, and a slug of deformable material in the set screw bore to be advanced against the member to be anchored by rotation of the pressure screw.
